UNITED STATES PATENT OFFICE.

EDMUND F. HARTSHORN, OF NEWARK, NEW JERSEY, ASSIGNOR TO STEWART HARTSHORN COMPANY, OF EAST NEWARK, NEW JERSEY, A CORPORATION OF NEW JERSEY.

SHADE-ROLLER.

1,202,286.

Specification of Letters Patent.

Patented Oct. 24, 1916.

Application filed June 4, 1914. Serial No. 842,822.

To all whom it may concern:

Be it known that I, EDMUND F. HARTSHORN, a citizen of the United States, residing in the city of Newark, county of Essex, State of New Jersey, have invented a certain new and useful Improvement in Shade-Rollers, of which the following is a specification.

The invention relates to rollers of the type wherein no pawl is used and which are particularly applicable for car windows, in which the curtain or shade is held in expanded position by a fastening device adjacent to the lower edge thereof.

15 The principal object of the invention is to provide a device for locking the spring in wound-up condition when the roller is removed from its brackets, so that it may be replaced without the spring unwinding. 20 This and further objects will more fully appear from the following specification and accompanying drawings, considered together or separately, in which:

Figure 1 is an elevation of part of a window frame showing a shade and roller embodying my invention; Fig. 2 is a longitudinal section of the roller; Fig. 3 is a transverse section on the line 3 of Fig. 2, looking in the direction of the arrow; Fig. 4 is an 30 enlarged sectional view of the spear end of the roller; Fig. 5 is a transverse section thereof on the line 5—5 of Fig. 4, looking in the direction of the arrow, and showing the parts in unlocked position; Fig. 6 is a similar view, showing the parts in locked position; and Fig. 7 is an end view of the spear and locking arms.

In all of the views, like parts are designated by the same reference characters. 40 In the drawings, the window frame 1 is provided, as shown, with the usual hood 2, which conceals the roller from view. The roller 3 carries the shade 4. One end of the roller is supported in the pin bracket 5. 45 The other end of the roller is supported in the spear bracket 6. This latter bracket has the usual notch by means of which the spear may be lifted out. The end of the roller is inclosed by means of a cap 7. This cap has 50 a central opening forming a bearing for the spear 8. The spear is connected to a rod 9. Surrounding this rod is the usual spring 10 with one end connected to the cap so that the roller will be rotated by the unwinding 55 of the spring.

A groove 11 extends longitudinally on the roller. In this groove 11 is a wire 12. The shade is doubled over the wire as shown. It is thereby held in place within the groove. There is a notch 13 in the cap in line with the groove. On the spear is an arm 14. When the shade is in the usual operative position this arm 14 will turn clear of the end of the wire 12. By sliding the wire and shade longitudinally it is brought within the path of rotation of the arm 14, and the arm engaging with the wire will be prevented from rotating. This wire, therefore, serves as a shade support, and by a longitudinal movement, the wire, in connection with the arm, serves as a means, actuated by the movement of the wire, to lock the spring in wound-up condition. I have shown the arm 14 as projecting from opposite sides of the spear, but such an arrangement is solely for purposes of illustrating the principle of the invention.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is:

1. A shade roller having a spear and a spring, a longitudinal groove in the roller, means for supporting a shade in the groove, said means being movable longitudinally and means actuated by such movement to lock the spring against unwinding.

2. A shade roller having a spear and a spring, a longitudinal groove in the roller, means for supporting a shade in the groove, said means being movable longitudinally of the roller, and an arm carried by the spear and interposed in the path of the shade supporting means, whereby when the supporting means are moved longitudinally the spring will be locked against unwinding.

3. A shade roller having a spear, a spring, and a longitudinal groove, a shade supporting wire within the groove capable of longitudinal movement, and means actuated by such movement to lock the spring in wound-up condition.

4. A shade roller having a spear, a spring,

and a longitudinal groove, a shade supporting wire within the groove capable of longitudinal movement, and an arm carried by the spear and rotating in the path 5 of the wire, when longitudinally moved, whereby the spring will be locked in wound-up condition.

5. A shade roller having a spear, a spring and a longitudinal groove, a shade supporting wire within the groove and capable of longitudinal movement, and an arm carried by the spear and engaged by the wire when the latter is moved longitudinally.

6. A shade roller having a spring, a spear 15 and a longitudinal groove, a member within the groove, said member being capable of longitudinal movement, and means carried by the spear to be engaged by the member when the latter is moved longitudinally.

20 7. A shade roller having a spear and a spring, a member carried by the roller and extending the full length thereof, means for moving said member longitudinally of the roller, and means actuated by such member 25 to lock the spring against rotation.

8. A shade roller having a spear and a spring, a longitudinal groove extending the entire length of the roller, a member within 30 the groove and extending the full length of the roller, means for moving the member longitudinally of the roller, and means en-

gaged by said member to lock the spring against rotation.

9. A shade roller having a spear, an arm carried by the spear, a spring, connections 35 between the roller and spring whereby the spring is moved relatively to the spear, a manually operated member carried by the roller and extending longitudinally thereof for its entire length, and means for moving 40 the member relatively to the roller whereby the roller and spear are locked against relative movement.

10. A shade roller having a spear, an arm carried by the spear, a spring, connections 45 between the roller and spring whereby the spring is moved relatively to the spear, a longitudinal groove extending the entire length of the roller, a manually operated member carried in the groove and extending longitudinally thereof for its entire 50 length, and means for moving the member relatively to the roller to engage the arm whereby the roller and spear are locked 55 against relative movement.

This specification signed and witnessed this second day of June, 1914.

EDMUND F. HARTSHORN.
